(57) **CLAIM**

The ornamental design for a prosthetic foot, as shown and described.

DESCRIPTION

FIG. 1 is a front perspective view of a prosthetic foot showing our design;

FIG. 2 is a rear perspective view of the prosthetic foot of FIG. 1;

FIG. 3 is a front elevation view of the prosthetic foot of FIG. 1;

FIG. 4 is a rear elevation view of the prosthetic foot of FIG. 1;

FIG. 5 is a left side view of the prosthetic foot of FIG. 1;

FIG. 6 is a right side view of the prosthetic foot of FIG. 1;

FIG. 7 is a top plan view of the prosthetic foot of FIG. 1; and,

FIG. 8 is a bottom plan view of the prosthetic foot of FIG. 1. The broken line showing is included for the purpose of illustrating environment and forms no part of the claimed design.
